Filed June 14, 1962, Ser. No. 202,483
5 Claims. (Cl. 338—151)

This invention relates to rheostats and more particularly to high current, low impedance, infinitely variable resistance devices.

Prior art rheostats are designed with many characteristics suitable for performing numerous specialized operations. Although forced cooling of rheostats is known in environments requiring resistance dissipation of large amounts of power and rheostats utilizing mercury pool contacts are known, a combination of these arrangements to provide control of hundreds or thousands of amperes has not been fully exploited. There remains a problem of obtaining infinitely variable low impedance control of large battery currents of up to several thousand amperes.

Therefore, an object of the present invention is to provide an improved high current, infinitely variable, liquid contact rheostat.

In accordance with one embodiment of my invention, a plurality of hollow arcuate resistive elements are rotatable to engage mating mercury pools. The mercury electrically couples the resistive elements to a contactor, thus forming a rheostat. Means are provided for pumping through the elements and the contactor respectively, a cooling fluid which results in a capability of this invention for regulating large amounts of current without destructive heating of the conducting resistive elements. A simple arrangement for accomplishing necessary parameter control is attained by sensing the critical parameter and adjusting the positions of the rheostat resistive elements to accomplish any correction necessary. For instance, the load current may be sensed with the rheostat position being adjusted to maintain a desired constant current flow despite impedance variations of the system because of thermal variations of impedance components.

The subject matter which is regarded as my invention is particularly pointed out and distinctly claimed in the concluding portion of this specification. The invention, however, as to its organization and operation, together with further objects and advantages thereof, will best be understood by reference to the following description taken in connection with the accompanying drawing in which:

FIG. 1 is a simplified schematic diagram illustrating one use of the present invention in a parameter sensitive environment requiring substantial current and power regulation;

FIG. 2 is a side elevation view partially in section of one embodiment of my invention; and

FIG. 3 is a cross-section view taken along the line of 3—3 of FIG. 2.

Referring now to the drawing, wherein like numbers refer to similar parts, I show in FIG. 1 a rheostat 10 of the present invention arranged in a circuit diagram. In this circuit an arc plasma generator 12 is arranged to apply heated gas to a test model 14. After such an arrangement will be utilized to test ablation characteristics, wherein the average temperature of the gas impinging on the model 14 is of the order of 3,000 to 5,000° K. The attaining of such a temperature usually requires electron temperatures within the arc of the order of 15,000 to 20,000° K.

The arc generator 12 comprises two electrodes 15 and 16. The electrode 15 is preferably of a refractory metal such as tungsten but in some applications may be a com-

pacted graphite rod, and the electrode 16 is a subsonic or a supersonic nozzle arrangement formed of a conductive material such as certain copper alloys. Other primary circuit components include a battery power supply 18 having an internal resistance represented schematically by a rheostat 19, a double contact circuit breaker 20 and a fixed ballast resistor 22. The circuit breaker 20 is closed to initiate current flow and is biased open upon release by the action of trip solenoid 23 to terminate current flow. The ballast resistor 22 is provided to limit initial maximum current flow.

The maintaining of a predetermined flow of heated gas from the arc generator 12 turns out to be a relatively complex problem. Gas supplied through line 24 is applied to the arc, preferably through a plurality of choked supersonic nozzles 25 exiting into an insulating housing 26, whereby the particular internal pressure of the system will not materially affect the rate of gas flow. The gas flows from the housing 26 through the region of the arc and is heated thereby. Several gases may be used in an arc generator of this type including air, argon, helium and nitrogen. However, the rate of flow of gas 24 may not be varied over a wide range for a given arc without suffering extinguishing of the arc. Therefore, an additional plenum chamber 28 is provided whereby additional amounts of gas may be introduced to the system through a control valve 29 to regulate the total mass of gas flow and the temperature of the gas impinging on the model 14. The plenum chamber 28 also operates much in the manner of a muffler to diffuse shock gas fronts and dampen the effects of arc fluctuation and, further, provides a region of low velocity suitable for measuring the stagnation pressure of the gas jet.

Use of the battery power supply 18 provides a desirable source of ripple-free current not readily attained when using alternating current or rectifier-type power supplies. However, batteries supply current at an essentially constant voltage and desired smooth current variation is accomplished by a change of the system resistance. For arc generator operation requiring a programmed change of current, the ohmic variation is produced by the rheostat 10 of my invention. In one arrangement, a circuit current signal is generated in a shunt around ammeter 30 and applied to a reference network 32 which generates an error signal 34. The error signal 34 is applied to a control field 36 of a selsyn-type positioning motor 38 which is drivingly coupled to the rheostat 10. Any error signal 34 will energize the motor 38, to reposition the rheostat 10 in accordance with a reference voltage applied within the network 32. The reference voltage may be programmed to simulate various phenomena.

In order to produce transient ablation of the test model 14 for simulation of nose cone re-entry heat transfer rates, programmed variation of the current supplied to the arc generator 12 will be a standard operating procedure. It is well known in the art that the arc operating voltage will remain essentially constant over a wide range of current flow. Thus the power dissipated in the arc and applied to the model 14 is directly proportioned to the current controlled by my invention. By way of example, when the battery power supply 18 is comprised of 320 12.5 volt storage batteries arranged in a series parallel array to give a fixed supply voltage of 250 volts, a current of 1500 amperes can flow through the arc generator 12. During such operation a voltage of about 100 volts directly across the electrodes 15 and 16 is typical.

With the rheostat 10 initially positioned to provide zero ohms the resistance of the rheostat 19 and fixed ballast resistance 22 will develop the remaining 150 volt drop of the circuit. By increasing the resistance of rheostat 10 the current can be made to decrease thus changing the

power of the arc and the heat-transfer rate to the model 14. Using specially designed batteries, a typical value of total battery internal resistance in such a series parallel array is $4.65 \times (10)^{-3}$ ohms leaving $9.53 (10)^{-2}$ ohms to be made up by the fixed ballast resistor 22 to limit the initial current to the 1500 amperes maximum. Changing the resistance of rheostat 10 during a desired period of time from zero to 0.2 ohm will change the power applied to the arc by a factor of nearly two. This variation is most simply accomplished by variation of the reference voltage in the network 32 to establish the zero setting of the error signal 34. Small undesirable changes in current flow due to heating effects in the batteries, rheostats, etc., will be compensated for automatically by operation of the rheostat 10 in accordance with the error signal 34.

In the event that excess currents do flow in the circuit, they will also be sensed in the ammeter shunt and applied to an overcurrent relay 39, which will operate the trip solenoid 23 in a manner well known in the circuit breaker art. Obviously, the error signal 34 may be replaced by a manual operation, when the reference network 32 includes an ammeter dial. Also, programming may be manually effected. However, a more sophisticated arrangement as indicated often will provide a smoother transition.

Referring now to FIG. 2, I show in detail the rheostat 10 of my invention which is capable of continuously conducting many hundreds of amperes while at the same time having a controlled and infinitely variable impedance. Empirical data indicate that a stepped variation of the impedance in the circuit adversely affects the operation of the arc jet and often produces inaccurate test data. Therefore, I have provided a plurality of rotatable annular nichrome tubular resistive elements 40. Using nichrome elements having a peripheral length of about 20" and a diameter of $\frac{1}{4}$ " with a wall thickness of .005", the resistive elements 40 will each continuously conduct about 400 amperes when they are forced-circulation cooled by room temperature water at 60 p.s.i. and at a flow rate therethrough of 10' per second. The flow rate of 10' per second is approximately 12 gallons per minute when using eight resistive elements as shown in FIG. 2. A pump 41 easily supplies this flow rate in a completely pressurized system, and by enlarging the pump 41 the output water may be dumped in arrangements where no large storage capacity is available. Also, in using the present invention, where distilled water is unavailable scaling should be removed periodically.

In this particular application the resistive elements 40 each have a maximum resistance of about 0.2 ohm and are arranged each to conduct as much as 400 amperes without destructive heating. The coolant water flows in the direction of arrows 42 through a coupling 43 into a rotatable central support pipe 44, through insulating coupling pipes 46, and elbows 47, through the nichrome resistive elements 40 and elbows 49 to a coolant header 48 and out through a coupling 50. The coolant header 48 also functions as a current collector bus bar for coupling together a plurality of the resistive elements 40. In one arrangement the coupling pipes 46 are of Teflon and the other coupling elements are chrome-plated copper tubes and elbows. Chrome plating is resistive to mercury vapor corrosion. In order that high pressure water may be pumped through this system, a rotatable seal is provided in the form of O-rings 51 and 52 at each of the couplings 43 and 50 respectively. Also, the pipe 44 is provided with a plug 53 for directing the water through the resistive elements 40.

As shown in FIG. 2, the mating contactor element comprises a mercury well contactor arrangement 54 defining a series of depressions or wells 55 which contain pools 56 of mercury to couple electrically the resistive elements 40 to the contactor 54. In order that the resistive elements 40 may be serially coupled, the contactor 54 is divided into a plurality of sections by insulating inserts

5 or washers 58. Thus, the flow of current as illustrated by dashed arrows 59 may be from left to right (FIG. 2) through the illustrated rheostat 10, from a terminal 60 to the first section of the contactor 54, through the first pair of resistive elements 40 and elbows 49 to the bus bar 48, through a second pair of resistive elements 40 to the second section of the contactor 54, through a third pair of the resistive elements 40, etc. The return of the current through the central resistive elements 40 to the central section of the contactor 54 is assured by the insertion of an insulating coupling 62 which divides the bus bar 48 into a plurality of sections.

Finally, the current flows from the last section of the contactor 54 to the output terminal 64. Obviously, the current flow may be arranged to pass between the contactor sections and the bus bar sections a greater number of times than that illustrated herein. Similarly, additional resistive elements may be stacked in parallel when it is necessary to provide increased current capacity.

It is preferable to arrange for the water coolant to flow in the direction of the arrows 42 (FIG. 2, 3) so that those portions of resistance elements 42 which are immersed in the mercury pools 56 are first to be cooled by the water to thus minimize heat transfer to the mercury. In this way the creation of noxious and corrosive mercury vapors can be avoided. For most effective and safest operation the water inlet temperature should be approximately 10° C. with a flow rate sufficient to keep outlet coolant temperature at or below 80° C. Should it be necessary to operate at higher coolant temperatures, in a manner well known the coolant system could be pressurized to increase the boiling point of the water and thus eliminate the possibility of localized boiling in resistance tubes 42.

As will be seen in viewing FIGS. 2 and 3 additional cooling for the mercury pools 56 is provided by having the area beneath wells 55 jacketed. In this jacketed area the pump 41 also forces the circulation of coolant fluid in a direction from left to right in FIGURE 2.

As discussed in connection with FIG. 1, regulation of the angular position of the resistive elements 40 is controlled by the motor 38. As shown in FIG. 2 the motor 38 is coupled to the rotatable pipe 44 through corrosion resistant reduction gearing 66. As a safety measure, excessive temperatures in the rheostat 10 are prevented and the elements 40 are protected from high exit water temperatures or water pressure failure by a combined temperature and pressure actuated relay 67 which is also coupled to the trip solenoid 23 and will energize it in the event of high temperature or low pressure. Protective controls of this type are well known in the heating industry and need not be explained in detail here. An additional safety feature is provided in the form of a finger or stop 68 positioned on the outer surface of the rotatable equipment (the trailing edge of at least one elbow 47) to engage an abutment 69 (FIG. 3) in the well 55 and thus prevent substantial loss of contact between the mercury pool 56 and the elements 40, when a maximum amount of resistance has been provided.

Since I am utilizing mercury contacts, I prefer to enclose the rheostat 10 within a vapor tight housing 70 having a removable top portion 71. The housing 70 is filled with a pressurized gas such as dry nitrogen to minimize corrosion on the metallic surfaces. The nitrogen gas is introduced through a charging valve 72 and the pressure is indicated by a gauge 73.

FIG. 3 is a cross-section view of the rheostat 10 and shows the annular configuration of one resistive element 40, the central location of the central pipe 44, the insulating pipe 46 and the relative location of the bus bar header 48. The electrical current flow is illustrated by the dashed arrow 59 and the coolant water flow is illustrated by the solid arrow 42. FIG. 3 also illustrates insulating support straps 74 which engage the elements 40 by means of loops 75 to maintain them a fixed radial distance from central pipe 44. To maintain the arcuate re-

sistance elements 40 fixed longitudinally of central pipe 44 and to generally rigidize the assembly, aligned hollow spacers 77 are interposed between adjacent straps 74, and tie rods 76 are secured through the spacers 77 and the holes in the straps 74. These tie rods 76 and spacers 77 5 will withstand any mechanical vibrations and magnetic forces that might tend to move the resistance elements relative to each other and relative to the mercury pools. Using no more than about 20" resistive elements 40 with no more than 400 amperes flow through each element, 10 additional cross bracing is usually unnecessary.

As is also illustrated in FIG. 3 each of the resistive elements 40 is provided with a substantial arcuate gap 78 which may be positioned in the region of mercury pool 56 when the equipment is not in use. In this manner, 15 corrosion of the nichrome tubing caused by extended contact with mercury may be eliminated.

While I have shown and described a particular embodiment of the present invention, further modifications may occur to those skilled in this art. For instance, although I have described in some detail one environment requiring the infinitely variable rheostat of my invention, this invention may be used in numerous applications for controlling large battery currents and the like. I desire it understood, therefore, that my invention is 20 not limited to the particular form disclosed and I intend by the appended claims to cover all such modifications which do not depart from the true spirit and scope of my invention.

I claim:

1. An infinitely variable, high current rheostat for regulating hundreds of amperes in an environment sensitive to relatively small current variations, comprising:
a plurality of parallel hollow annular resistive elements 30 adaptable for conducting large electric currents and substantial coolant fluid;
a centrally disposed rotatable support pipe coupled to one end of each of said elements by means of an insulated hollow coupling, respectively;
a bus bar header both electrically and hydraulically coupled to the opposite ends of said elements;
a contactor defining upwardly opening arcuate wells arranged to encompass an arcuate portion of each of said elements respectively;
a mercury pool within each of said wells for electrically 35 coupling said contactor to said elements;
insulating means for dividing said contactor into a plurality of sections so that the only coupling therebetween is through a plurality of said elements;
means for detecting the current flow through the rheostat; and
means for rotating uniformly said elements relative to 40 said contactor to vary the impedance between said mercury pools and said header and thereby regulate the voltage between said contactor sections while maintaining a programmed current flow of the order of hundreds of amperes through the rheostat.
2. An infinitely variable, high current rheostat for use in a circuit arranged to conduct a programmed current flow of the order of hundreds of amperes, comprising:
a plurality of parallel hollow annular resistive elements 60 adaptable for conducting large electric currents and substantial coolant fluid;
a centrally disposed rotatable support pipe arranged to support one end of each of said elements;
means for electrically insulating said elements from said pipe;
a bus bar header both electrically and hydraulically coupled to the opposite ends of said elements;
a contactor defining upwardly opening arcuate wells 65 arranged to encompass an arcuate portion of each of said elements respectively;
a mercury pool within each of said wells for electrically coupling said contactor to said elements;

insulating means for dividing said header into a plurality of sections so that the only coupling therebetween is through a plurality of said elements;
means for forcing coolant fluid through said elements so that it flows from the region of said pools toward said header;

means for detecting the current flow through the rheostat; and

means for rotating uniformly said elements relative to said contactor to vary the impedance between said mercury pools and said header and thereby vary the voltage between said header sections while maintaining a controlled current flow through the rheostat.

3. An infinitely variable, high current rheostat for use in a circuit arranged to conduct a programmed current flow of the order of hundreds of amperes, comprising:
a plurality of parallel hollow annular resistive elements adaptable for conducting large electric currents and substantial coolant fluid;

a centrally disposed rotatable support conduit arranged to support one end of each of said elements;
means for electrically insulating said elements from said conduit;

a bus bar header both electrically and hydraulically coupled to the opposite ends of said elements;
a contactor defining upwardly opening arcuate wells arranged to encompass an arcuate portion of each of said elements respectively;

a mercury pool within each of said wells for electrically coupling said contactor to said elements;

insulating means for dividing said contactor into a plurality of sections so that the only coupling therebetween is through a plurality of said elements; and
means for forcing coolant fluid through said elements so that it flows from the region of said pools toward said header to thereby minimize the temperature variation of said pools during prolonged operation of the rheostat.

4. An infinitely variable, high current rheostat for use in a circuit arranged to conduct a programmed current flow of the order of hundreds of amperes, comprising:
a plurality of parallel hollow annular resistive elements adaptable for conducting large electric currents and substantial coolant fluid;

a rotatable support conduit arranged to support one end of each of said elements;
means for electrically insulating said elements from said conduit;

a bus bar header both electrically and hydraulically coupled selectively to the opposite ends of said elements;

a first terminal;

a first mercury pool for electrically coupling said first terminal to one of said elements;

a second terminal;

a second mercury pool for electrically coupling said second terminal to another of said elements;

means for forcing coolant fluid through said elements so that it flows from the region of said pools toward said header to thereby minimize the temperature variation of said pools during prolonged operation of the rheostat; and

lateral support means between said elements for preventing substantial reaction thereof to magnetic forces therebetween.

5. An infinitely variable, high current rheostat for use in a circuit arranged to conduct a programmed current flow of the order of hundreds of amperes, comprising:
a plurality of parallel hollow annular resistive elements adaptable for conducting large electric currents and substantial coolant fluid;

a rotatable support conduit arranged to support one end of each of said elements;

means for electrically insulating said elements from said conduit;

a bus bar header both electrically and hydraulically coupled to the opposite ends of said elements;
 a first terminal;
 a first mercury pool for electrically coupling said first terminal to one of said elements;
 a second terminal;
 a second mercury pool for electrically coupling said second terminal to another of said elements; and
 means for forcing coolant fluid through said elements so that it flows from the region of said pools toward said header to thereby minimize the temperature variation of said pools during prolonged operation of the rheostat.
